DESIGN FOR A RECESSED TYPE BATHROOM FIXTURE

Henry Gruen, New York, N. Y.

Application February 5, 1948, Serial No. 144,307

Term of patent 14 years

(Cl. D4—3)

To all whom it may concern:

Be it known that I, Henry Gruen, a citizen of the United States, residing at New York city, county of Bronx, and State of New York, have invented a new, original, and ornamental Design for a Recessed Type Bathroom Fixture, of which the following is a specification, reference being had to the accompanying drawing, forming a part thereof.

Fig. 1 is a view in front elevation of a recessed type bathroom fixture embodying my design.

Fig. 2 is a section on the line s2—s2 of Fig. 1, and

Fig. 3 is a section on the line s3—s3 of Fig. 1.

I claim:

The ornamental design for a recessed type bathroom fixture, as shown and described.

HENRY GRUEN.
